UNITED STATES PATENT OFFICE.

MATTHEW J. OWENS AND FRANCIS M. OWENS, OF BOSTON,
MASSACHUSETTS.

DESIGN FOR AN ADVERTISING-BADGE.

SPECIFICATION forming part of Design No. 34,390, dated April 23, 1901.

Application filed March 28, 1901. Serial No. 53,367. Term of patent 3½ years.

To all whom it may concern:

Be it known that we, MATTHEW J. OWENS and FRANCIS M. OWENS, citizens of the United States, and residents of Boston, county of Suffolk, and State of Massachusetts, have invented and produced a new, useful, and original Design for an Advertising-Badge, of which the following is a specification, reference being had to the accompanying drawings, forming a part thereof.

Figure 1 is a plan view of the obverse face of an advertising-badge, illustrating our design. Fig. 2 is a similar view of the reverse face of the badge; and Fig. 3 is a diametral section on the line $x x$, Fig. 1.

The leading feature of our design for an advertising-badge consists of a flat annular body having upon its obverse face the representation of two interlocked horseshoes and upon its reverse face the representation of portions of the leaves and stem of a four-leaf clover.

The flat annular body a has upon its obverse face a' the representation, in relief, of two interlocked horseshoes, the toe parts 25 whereof surround and are concentric with the central opening a^x of the body, and on the reverse face a^2 the outer portions of the leaves of a spray of four-leaf clover are represented, also in relief, with a portion of the stem arranged about the opening a^x .

Having fully described our design, what we claim, and desire to secure by Letters Patent, is—

The design for an advertising-badge, substantially as herein shown and described.

In testimony whereof we have signed our names to this specification in the presence of two subscribing witnesses.

MATTHEW J. OWENS.
FRANCIS M. OWENS.
